VACUUM CLEANERS

Elmer L. Hoffmann, Park Ridge, and Bernhardt B. Bruggen, Berwyn, Ill., assignors to Raymond T. Moloney

Application December 30, 1948, Serial No. 68,256

4 Claims. (Cl. 15—402)

This invention pertains to vacuum cleaners, particularly but not exclusively, toy cleaners, it being understood that numerous features of construction and operation of the device disclosed hereinafter are applicable with equal effectiveness in standard utility vacuum cleaners.

Among the principal objects and improvements characterizing the mechanism hereinafter described are: A provision of simplified structural components favorable to large scale, economical manufacturing processes with regard both to the production and assembly of parts.

More particular objects are the provision in a vacuum cleaner of a main housing element which may be cast and molded as a single unit and particularly characterized in that it has an integrally formed suction chamber in an upper face with integrally formed terminal for attachment to the dust bag, and an integrally formed intake or pickup chamber in a lower face thereof.

Additional objects and aspects of novelty and utility pertain to details of construction and operation of the embodiment described hereinafter in view of the annexed drawings, in which:

Fig. 1 is a vertical section through the working unit of the cleaner;

Fig. 2 is a top plan view of the unit of Fig. 1, with the dome removed and disclosing the motor subassembly;

Fig. 3 is a bottom plan view of the main housing shell with the closure comb removed;

Fig. 4 is a bottom plan view to smaller scale of the main housing shell with the closure comb in position;

Fig. 5 is a top plan view of the main housing shell with the motor subassembly removed to expose the suction chamber;

Fig. 6 is a fragmentary top plan view of the handle switch mechanism in the on position;

Fig. 7 is a view similar to Fig. 6, with the handle switch in off position and the handle lock engaged;

Fig. 8 is a side elevation of the complete cleaner;

Fig. 9 is a fragmentary median detail, showing parts in section, of the jointed handle and bag hook means;

Fig. 10 is a schematic circuit detail of the motor transformer means for procuring headlight voltage;

Fig. 11 is a fragmentary perspective view of the rear of the dome shell.

Referring to the general assembly shown in Fig. 8, the cleaner includes the working unit generally indicated at 15, which in turn includes a lower housing shell 16 and a dome shell 17, from specially formed openings in which protrudes a rockable handle mount 18, into which is telescopingly fitted the lower section 19 of handle tube, having an upper tubular section 20 telescopingly fitted thereto as at 21 by means of the reduced or swedged formation 22 (Fig. 9), which provides an annular seat for bag hook 23. The general assembly is completed by the usual dust bag 24 suspended at its upper end from hook 23 and coupled by elastic band at its lower end to the discharge nozzle

2

25, which forms an integral part of the lower shell (Fig. 5).

As viewed in Fig. 5, the lower shell 16 on its upper face has an integrally formed fan chamber 30 communicating from the nozzle formation 25 in a rear wall of the shell through an intake opening 31 to the bottom of the chamber.

As viewed in Fig. 3, the main housing shell 16 on its underside includes the annular skirt portion or wall 16A (see also Fig. 8) and the internally pendant or depressed portions 30A of the suction chamber, which is shown also to advantage in Fig. 1, together with reinforcing ribs 33 and 34 and certain comb mounting bosses 35 and wheel mounting bosses 36, it being observed that the rib portions 34 have transverse ribs 37.

As in Fig. 3, wheels 38 are mounted by pins 39 on T-shaped brackets which include a cross-member 40 apertured to seat on the cross-ribs 37 with bosses 36 passing therethrough, said brackets being held in place by gripper wafers 41 engaging certain of the bosses 36, as shown also to advantage in Fig. 1.

Referring to Fig. 2, the motor subassembly includes a mounting plate 44 of size sufficient to close the suction chamber 30, said plate being retained by gripper wafers 25 engaged with integral wafers 46 and further positioned by bosses 47 engaged in notches in the plate, together with a thrust rib 48 at the leading edge of said plate, which rib is grooved as at 49 to receive the window glass for the headlight.

A motor, including the usual field core 50 and winding 51, is mounted on a pair of posts, one of which is indicated at 52 in Fig. 6, and both of which have reduced upper coreposts 53 (Fig. 2) projecting upwardly through the core and engaged by retaining wafers 54.

In Fig. 1 the motor will be observed to have a shaft 55 depending into the suction chamber 30 where it is frictionally gripped by hub portions 56 on a molded plastic turbine or blower-rotor 57 (see also Fig. 3). The rotor 57 includes integral blades 58, and has its hub 56 split as at 56A to afford a forced fit with shaft 55.

The otherwise open bottom of the shell 16, as it appears in Fig. 3, is closed by a combination comb and closure plate 60 shown in Fig. 4, and which is preferably constructed of a material such as fibre which will have an amount of rigidity, some yieldability, and a minimum of cutting hardness.

The plate 60 has a transverse suction slot 61 stamped therein with a plurality of outturned teeth 62 formed along the rear or trailing edge thereof, as shown to advantage also in Fig. 1.

The terminals of the transverse comb slot are enlarged as at 63 to accommodate the wheels 38, and the leading edge of the slot is turned inwardly as at 64 (Fig. 1 also) to provide a deflecting edge for the inflowing air stream. The necessity for rear wheels is eliminated by the provision in the comb plate of a plurality of gliding boss formations 65 and 66 stamped therein. An angular rib 67 is embossed in the plate inwardly to fit against the reinforcing ribs 33 of the main shell further securing the comb plate against rearward displacement and also providing a deflector leading upwardly from the comb 62 beneath the air intake opening 31 in the suction chamber. Drive pins 69 inserted in bosses 65 secure the comb plate in position.

As viewed in Fig. 2, the rockable handle mount 18 includes a yoke portion with divergent trunnion offsets 18A pivotally engaged in straps 70 riveted as at 71 to plate 44 (see Fig. 6 also).

A switch-operating plate 74 (Figs. 6 and 7) is mounted to slide on the base plate 44 by means of an elongated central slot 75 which is fitted onto the reduced lower end portion 52A of one of the motor mounting posts 52,

there being a pair of upset ears 76 in the base plate engaging an edge of the switch-operating plate to guide the latter in reciprocatory movement effected by the handle member 18 through the agency of an arm 77 upset from the operating plate 74 and having pin and slot connection as at 78 (Figs. 1, 2, 6, and 7) with one of the hook arms of the handle mount 18.

Over-center or toggle-type snap-switch 80 (Figs. 1, 2, 6, and 7) is mounted on the subassembly plate 44 and includes an operating yoke 81 cooperable with a pin 82 on the slide plate 74, such that reciprocation of the latter between the on and off positions of Figs. 6 and 7 as by rocking the handle correspondingly will snap the switch into off and on positions.

Means for locking the handle in raised and off position includes a lock consisting of a pair of upset lugs 85 struck up from plate 44 to which is secured V-shaped spring catch 86 having a nose opening punched in the apex of the V as at 86A, Fig. 6, to provide opposite yieldable keeper formations 87 which grip the nose portion 88, Fig. 7, of locking lug 89 on the switch slide plate when the latter is advanced to the position of Fig. 7, in which condition the handle means 18, 19, and 20 would be in a substantially vertical position with the switch 80 snapped to off position.

The headlight assembly includes a socket 90 mounted on bracket 91 fixed to plate 44.

As indicated in the circuit diagram of Fig. 10, the lamp 92 is energized from a step-down winding 93 shown to be connected to the lamp by conductors 94, and which winding has induced therein a relatively low voltage from the field set up by the main winding 95 for the motor field. The motor winding 95 is intended to be energized from the standard commercial lighting circuit through conductors 96 including the main operating switch 80, and a safety factor is introduced by applying a stepped-down voltage of the order of 6-8 volts for head-lamp 92.

A further feature is the location of the low-voltage winding on the outside of the motor winding, whereby to afford a metallic shield, the resistance of said shield winding being high to limit the load current to afford a safety factor against both short-circuit and shock loads. This contrivance not only protects all users of the machine, particularly children, but reduces costs by eliminating a protective metallic shield for the motor or transformer, otherwise required.

The construction of the cleaner is completed by provision of a dome shell 17, Fig. 1, preferably molded from plastic with a window opening in the region 17A, which opening has three of the four sides of a frame for the window glass 98, the fourth side of the frame being provided by the thrust rib 48 in the main shell.

As indicated in Fig. 11, it will be observed that the dome shell 17 is provided with a pair of deep slots 17B and three wall portions 17C and 17D in which the hook portions of the handle element 18 may rock back and forth, the recessed wall portions 17C and 17D nevertheless substantially closing off these slots, excepting at their open bottom portions 17E.

We claim:

1. In a vacuum cleaner, a main housing shell having at least two sets of crossed reinforcing ribs on opposite sides thereof, and wheel mounts including wheel-supporting brackets each having a longitudinal section intersecting a crosswise section and each mounted on a set of said crossed ribs with their respective longitudinal sections each resting along one rib of the corresponding set and their respective crosswise sections each resting along the corresponding crosswise rib portion, each said set of ribs having boss formations engaged in the corresponding wheel bracket, and bracket-securing means engaged with said bosses.

2. In a suction cleaner, a housing shell comprising a top wall having an integral, depending, circumambient skirt defining a bottom chamber, and having a depressed

well extending down into said chamber and constituting a fan chamber, the latter having an intake opening communicating into said bottom chamber, and said well opening upwardly through the plane of said top wall and further including a discharge extension opening upwardly through said plane and also leading through said skirt into conjunction with an integral bag flange; a motor-fan subassembly including a base plate carried on said top wall and closing off said well and discharge passage portions in the top wall and having a fan extended into said well; said shell having an integral web extending between opposite sides of said skirt in said bottom chamber dividing the latter to form a suction chamber communicating with said intake opening in the fan chamber; said shell further having a set of integral, crossed webs in said bottom chamber and situated at opposite sides of said suction chamber therein and providing wheel supports; and a bottom closure plate fitted into said bottom chamber to close the latter substantially in its entirety, said plate including an elongated suction slot overlying said suction chamber and having integrally offset combing teeth struck downwardly out of the plane of said plate, together with at least two wheel openings there-through; and wheel means including a crossed bracket member seated upon each of said crossed-web wheel supports and each said bracket member carrying a wheel adapted to project through one of said wheel openings.

3. In a suction cleaner, a main housing shell having a bottom chamber defined by a top wall and a surrounding sidewall, said top wall being adapted to support a suction mechanism for drawing air-borne soil through said bottom chamber; said shell including an integral dividing web in said bottom chamber defining a suction chamber, said web being situated approximately in the median transverse regions of said bottom chamber; a pair of axially aligned gliding wheels in said suction chamber and projecting beyond the margins of said sidewall to engage a gliding surface; a closure plate of fibrous material fitted into said bottom chamber at said sidewall margins to substantially close off said bottom chamber and overlie the latter and said wheels and dividing web; said plate having an elongated suction opening extending in parallelism with the wheel axis and terminating at opposite ends in enlargements each registering with one of said wheels and through which the latter project for gliding action as aforesaid, said suction opening having a series of offset combing teeth formed along at least one longitudinal margin thereof.

4. A construction according to claim 3 in which said plate is additionally provided with a plurality of elongated, substantially parallel extrusions directed normally of the wheel axis to define gliding ribs.
